UNITED STATES PATENT OFFICE.

GUSTAV ADOLPH OLSON, OF ALBERT LEA, MINNESOTA.

KNITTING-MACHINE.

SPECIFICATION forming part of Letters Patent No. 330,728, dated November 17, 1885.

Application filed June 5, 1885. Serial No. 167,710. (No model.)

To all whom it may concern:

Be it known that I, GUSTAV ADOLPH OLSON, a citizen of the United States, and a resident of Albert Lea, in the county of Freeborn, in 5 the State of Minnesota, have invented certain new and useful Improvements in Knitting-Machines, of which the following specification is a full, clear, and exact description, reference being also had to the accompanying drawings.

10 This invention relates, generally, to knitting-machines for knitting stockings, socks, and similar garments; and it consists, specifically, in an attachment whereby the heel-forming mechanism may be operated automatically, 15 as herein described, and pointed out in the claims.

In the drawings the invention is shown attached to the knitting-machine known as the "Twombly" machine—such as shown and 20 described in Letters Patent No. 229,288, to Orison Twombly, June 29, 1880—to which it is peculiarly applicable.

Figure 1 represents a plan view, partly in 25 section, and Fig. 2 represents a rear view, of one of the above-mentioned machines with my improvement attached thereto. Fig. 3 is a detached perspective view of the pin-raising mechanism and one of the trip-plates. Fig. 4 is a detached perspective view of the pin-elevating cam-levers. Fig. 5 is a view of a portion of 30 the under side of one of the guide-plates and of the segmental plate, showing the construction and arrangement of the friction-spring which clasps one plate to the other.

35 In this machine, A represents the central shaft, rigidly attached to a standard adapted to be secured to a table, bench, or in any other stationary position, and having rigidly fixed to its lower end the needle-plate B' in which 40 the needles are arranged. The needles are not shown in the drawings, as they form no part of the invention; but I have simply shown the needle-plate provided with its recesses a for the reception of the needles. Above this 45 needle-plate B' is the cam-plate B², which is adapted to be revolved about the central shaft, A, by two beveled pinions, and having an upright fixed pin, D⁵. Only one of these bevel-pinions, B³, is shown in the drawings, the other 50 being attached to the standard, which is not shown.

Upon the under side of the cam-plate B² is

arranged the cam B⁴, (shown only in Fig. 2,) for operating the needles, and upon the upper part of the plate is shown the different 55 adjusting-levers, tension-bars, &c., connected with the knitting mechanism of the machine; but as these form no part of the present invention they need no further description.

Attached rigidly to the central shaft, A, 60 above the cam-plate B² and its pinion B³, is a segmental plate, C', provided with two rows of perforations, b' b², near its outer edge, and a V-shaped groove, d, concentric with its edge and between the perforations b' b² and the central shaft. 65

D' D² are two small trip-plates encompassing the outer edge of the segmental plate by being forked, as shown in Fig. 3, and having the forked parts embrace the segmental plate from 70 the outer edge thereof, the upper fork of each trip-plate having its bearing-surface at or near the outer and inner ends, as shown in the same figure, and running back a short distance across its top, and until they project 75 over the V-shaped groove d, and having pins h' h² passing down through them into the perforations b' or b². These trip-plates have grooves e in their lower sides, (see Figs. 2 and 3,) the respective sides of which grooves serve 80 to strike and trip a small lever, g, as they are moved around the edge of the segmental plate C'. Down through the rear ends of the trip-plates set-screws i' i² are adapted to be inserted, with their points fitting into the U-shaped 85 groove d, to serve as guides to the trip-plates and cause them to travel around the outer edge of the segmental plate concentric therewith.

The ordinary manner of operating the pins 90 h' h² in this machine is by removing and inserting them by hand, the two trip-plates D' D² being moved toward each other the distance of one of the perforations b' b² at each throw of the cam-plate B². 95

In knitting the straight portions of the stocking the trip-plates D' D² are not used, but are left off from the machine entirely, and the cam-plate B² is revolved continuously around the central shaft, A; but when the trip-plates D' D² are set in position on the segmental plate C' the cam-plate B² will be 100 simply oscillated between the hooked ends of the rods D³ D⁴ on the trip-plates, the pin D⁵

thus serving as a stop to regulate the distance which the cam-plate shall be moved.

In knitting and narrowing by hand according to the mode heretofore practiced, in first starting the heel portion of the stocking the trip-plates D' D² are set with their pins h' h², in the extreme outer perforations, b² b², and then after each movement or throw of the cam-plate B² the pins are removed and the trip-plates moved forward the distance of one perforation, and the pins h' h² inserted into the next perforation nearer the center of the rows of perforations, and so on, alternately, until the two trip-plates D' D² come together at the center, thus gradually forming a narrow, regularly-decreasing web of the knitted fabric, which will afterward form a portion of the heel-section of the stocking. The motion is then reversed, the pins h' h² being removed, and the trip-plates alternately moved away from each other the distance of one perforation, b², at a time, thereby forming another section of the heel portion of the fabric. This hand-adjustment of the pins h' h² is a very tedious and unsatisfactory process, requiring close attention and delicate manipulation of the pins to avoid "jumping" a perforation, and thus forming an irregularity in the fabric, as well as rendering it necessary to pause at each end of each row of stitches to move the trip-plates.

To automatically adjust the trip-plates D' D² upon the segmental plate C' by the motion of the cam-plate B² is the object of my invention, which consists of two guide-plates, E' E², formed with yokes E³ E⁴, fitting partially around the hub of the segmental plate C' and radiating outward and partially encompassing the trip-plates D' D², by extending out around the outer end thereof, and thence being bent back near the other edge of the same, forming a sort of hook, as shown in Fig. 1. At the points where these guide-plates E' E² pass over the V-shaped grooves d they are provided with pins m, which project down into the V-shaped grooves and form guides to the guide-plates, in the same manner as the set-screws i' i² form guides to the trip-plates D' D². Attached to the guide-plates E' E² by nuts or collars n' n', having internal screw-threads, are adjusting-screws n², by which the relative distances between the hooked ends E⁷ E⁸ of the guide-plates E' E² and the trip-plates D' D² may be adjusted, as hereinafter shown. On the outer ends of the guide-plates are pivoted reversible cam-plates E⁵ E⁶, the inner edges of which bear against springs t t. Passing through the pins h' h² (which are used in the same manner and in the same position and for the same purpose as the pins heretofore mentioned as being operated by hand to connect the trip-plates D' D² with the segmental plate C') are small rods or pins u' u², and beneath these pins and between them and the tops of the trip-plates D' D² are cam bars or levers F' F². The upper ends of the pins

h' h² are supported in brackets G' G², as shown. These levers F' F² are provided with open slots, down through which the pins h' h² pass, and with their upper surfaces inclining upward and outward at u⁵ u⁶, so that if they be pushed inward the inclined surfaces will pass beneath the cross-pins u' u² and raise up the pins h' h² and lift them out of the perforations b' b² and disconnect them from the segmental plate C'. The levers F' F² are extended by arms F³ F⁴, and each arm provided on its outer end with a small pivoted lever, F⁵ F⁶, each adapted to be turned off at right angles to its respective arm, and stopped by pins F⁷ F⁸, secured, respectively, to the arms F³ F⁴, from going beyond a right-angled position in either direction, as hereinafter more fully explained. The arms F³ F⁴ are adjustable lengthwise on the levers F' F² by slots and screws, as shown, so that the said levers of which the arms form a part may be lengthened or shortened. The brackets G' G² will each be attached, respectively, to plates G³ G⁴, the latter resting upon the upper surface of the trip-plates D' D² and made adjustable thereon by slots and set-screws i' i², as shown more clearly in Fig. 3, so that the pins h' h² may be adjusted to be set in either one of the rows of holes b' or b². Coiled springs u³ u⁴ are arranged to encircle the pins h' h² between the cross-pins u' u² and brackets G' G², to hold the levers F' F² down upon the trip-plates and forward in the position in which they are represented in Figs. 1 and 3, and also against the side of stops v' v² on the trip-plates. Attached at some suitable point of the cam-plate B² is a pin, H, projecting upward above and in front of the small pivoted levers F⁵ F⁶. In the drawings this pin H is shown projecting upward from the strap K', which supports the wheel or guide K², which serves to hold the knit web in place as the needles are thrust out in knitting; but it may be attached at any other suitable point.

When it is desired to move the trip-plates D' D² toward each other in commencing the knitting of the heel-section, each of the trip-plates is set with its pins h' or h² in the last perforation b' in the segmental plate C', and with the cam-levers F' F² turned so as to point away from each other, as shown in Fig. 1, and with the cam-plates E⁵ E⁶ also set pointing outward away from each other, as in Fig. 1, and with the small levers F⁵ F⁶ turned backward or toward the operating-pin H, as shown in Fig. 1. The cross-pins u' u² project for some distance from either side of the pins h' h², so that when the levers F' F² are in the position shown in Fig. 1 one end of each of the cross-pins will rest against one edge of each of the upright portions of the hangers or standards G' G², and the springs u³ u⁴ holding the pins u' u² downward with considerable force on top of the cam-levers F' F², the latter will thereby be held with some force against the stops v' v², when the levers are reversed, as well as forced

forward, by pressing on the outward and upward inclinations $u^5 u^6$, (shown most clearly in Fig. 4,) the inclinations being sufficiently steep to press the said cam-levers endwise. When 5 the cam-levers are located as shown in Fig. 1, the pins $u' u^2$ press upon the inclinations close to the lowest point or joining of the double inclination shown. As the cam-plate B^2 is revolved, the operating-pin H , striking the small 10 lever F^5 on the end of the arm F^3 , forces the entire levers $F' F^2$, with their inclined portions $u^5 u^6$, inward beneath the cross-pin u' , and lifts the pin h' from its position in one of the 15 perforations b' by its inclined upper surface passing beneath the cross-pin u' . This releases the trip-plate D' on the segmental plate C' , and enables the pressure of pin H on the lever F' to move the trip-plate around the distance of one of the perforations b' , or until 20 the pin h' comes above the next perforation.

The lower side of the plates $E' E^2$ are provided with springs $E^9 E^{10}$, which hold it with considerable force down in contact with the segmental plate, by pressing upward against 25 the lower surface of the said plate and clamping the same between them and the trip-plates to which they are attached.

The outer ends of each of the guide-plates $E' E^2$ are provided with backwardly-projecting hooked ends $E^7 E^8$, which project inward beyond the outer edges of the trip-plates $D' D^2$, as shown in Fig. 1. The distances between these hooked portions $E^7 E^8$ and the trip-plates $D' D^2$, when the latter are back in 35 contact with the set-screws n^2 , will be just about the distance between two of the perforations $b' b'$, so that the trip-plates are free to be moved between the hooked ends $E^7 E^8$ of the guide-plates $E' E^2$ and the set-screws $n^2 n^2$ 40 the distance of a pair of the perforations; hence when the operating-pin H comes in contact with the pivoted lever E^5 of the lever F' and moves it inward it raises the pin h' , and also moves the trip-plate D' around the segmental plate C' until the pin h' drops into the 45 next perforation, this movement at the same time throwing the trip-plate D' against the hooked portion E^7 of the guide-plate E' .

The two rows of perforations $b' b'$ in the 50 segmental plate C' are not of the same size or the same distance apart, the inner row being larger and farther apart than the outer row. The inner row of perforations will be used for coarse yarn, and the outer row for fine yarn, 55 larger needles and fewer being used for coarse knitting than for fine work, and the fewer holes in the inner row corresponding with the fewer coarse needles, and the hangers $G' G^2$ and pins $h' h^2$ will be adjustable upon the plates $D' D^2$ by the set-screws $i' i^2$, so that the pins $h' h^2$ may be adapted to either row of the perforations, and then the distance or throw of the trip-plate may be regulated by the set-screws n^2 .

55 The trip-plates $D' D^2$ will fit rather loosely upon the segmental plate C' , so that the press-

ure of the operating-pin H upon the levers $F' F^2$ will cause them to slip over the segmental plate just as soon as the pins h' or h^2 are clear of the segmental plate, while the springs $E^9 E^{10}$ 70 are much stronger than the springs $u^3 u^4$, so that when the trip-plates $D' D^2$ strike the hooked sections $E' E^2$ they will not move the guide-plates $E' E^2$ around out of their positions, so that the levers $F' F^2$, when the trip-plates $D' D^2$ strike the hooked sections $E' E^2$, 75 will be forced underneath the cross-pins $u' u^2$ and allow the operating-pin H to pass by the levers; then the springs, pressing down upon the cross-pins $u' u^2$, will throw the levers $F' F^2$ 80 outward again to their former positions by pressing down on their inclined surfaces $u^5 u^6$, which are sufficiently steep for the purpose; then the operating-pin H passes on until it strikes the outer point of the cam-lever E^5 or E^6 , upon which it will catch and throw the guide-plate E' or E^2 around until the set-screw n^2 strikes the trip-plate D' or D^2 . The pin h' or h^2 , having previously 90 dropped into its perforation, as before described, will hold the plate D' or D^2 fixed to the segmental plate C' ; hence when the set-screw n^2 strikes the trip-plate D' or D^2 the guide-plate E' or E^2 will be stopped, but the operating-pin H will force the cam-lever E^5 or 95 E^6 inward, overcome the tension of the spring t , and pass by it. The spring t will be strong enough to hold the cam-lever outward with sufficient power to overcome the tension of the spring E^9 or E^{10} on the guide-plate E' or 100 E^2 , so that the operating-pin H will move the guide-plate around until its set-screw n^2 strikes the trip-plate D' or D^2 . The operating-pin H will then travel around until it strikes the outer point of the other lever, F^2 , which it 105 will simply move backward away from contact with the stop v' or v^2 , and not affect anything. The cam-plate continues to revolve until the pin D^5 strikes the stop-hook D^3 or D^4 . Then at the return-stroke the operating-pin H pushes in the lever F' or F^2 , moves the trip-plate D' or D^2 the distance of one perforation, then catches upon the cam-lever E^5 or 110 E^6 , moves the guide-plate E' or E^2 around until its set-screw n^2 strikes the trip-plate D' or D^2 , then depresses the cam-lever against its 115 spring t , and continues around until it again strikes the lever F' or F^2 and takes up its former position again, ready for another stroke. By this means all that the operator is required to do is to oscillate the crank which moves the cam-plate B^2 , when the operating-pin H , acting upon the levers $F' F^2$, &c., will raise the pins $h' h^2$, move the trip-plates and 120 guide-plates forward alternately toward each other until they meet at the center, then, by placing the operating-pin H in a position between the levers $F' F^2$ and reversing the levers $F' F^2$ and their small right-angled levers $F^5 F^6$, and also reversing the cam-levers $E^5 E^6$ 125 and oscillating the cam-plate B^2 backward and forward as far as the stop-pin D^5 and the stop- 130

hooks $D^3 D^4$ will allow it to go, the pins $h' h^2$ will be lifted up from the perforations, and the trip-plates moved away from each other, one perforation at a time, for each stroke of 5 the cam-plate.

Having described my invention and set forth its merits, what I claim is—

1. The combination of the stationary needle-plate B' , cam-plate B^2 , provided with pins $D^6 H$, means for revolving the cam-plate, stationary segmental plate C' , provided with the perforations $b' b^2$, trip-plates $D' D^2$, pins $h' h^2$, cam-levers $F' F^2$, and devices, substantially such as described, connected with said pins 10 and intermediate of the same and the levers $F' F^2$, whereby when said levers are moved said pins may be lifted upward from said perforations in the segmental plate to release the trip-plates, and the latter may be moved upon 15 said segmental plate the distance from one of said perforations to the one next adjacent once during each stroke of said cam-plate, substantially as and for the purpose set forth.
- 20

2. The combination of the stationary needle-plate B' , cam-plate B^2 , provided with pins $D^6 H$, means for revolving the cam-plate, stationary segmental plate C' , provided with the perforations $b' b^2$, trip-plates $D' D^2$, pins $h' h^2$, standards $G' G^2$, springs $u^3 u^4$, cross-pins $u' u^2$, cam-levers $F' F^2$, provided with the pivoted 25 levers $F^5 F^6$ on their outer ends, guide-plates $E' E^2$, provided with laterally-extended and inwardly-turned portions encompassing the outer ends of said trip-plates, set-screws n^2 , springs $E^9 E^{10}$, and cam-levers $E^5 E^6$, substantially as and for the purpose set forth. 30

In testimony whereof I have hereunto set my hand in presence of two subscribing witnesses.

GUSTAV ADOLPH OLSON.
